UNITED STATES PATENT OFFICE.

ERNEST N. BRODERICK, OF DETROIT, MICHIGAN.

CARBURETER.

No. 892,499.

Specification of Letters Patent.

Patented July 7, 1908.

Application filed May 22, 1907. Serial No. 375,030.

To all whom it may concern:

Be it known that I, ERNEST N. BRODERICK, a citizen of the United States of America, residing at Detroit, in the county of Wayne and State of Michigan, have invented certain new and useful Improvements in Carbureters, of which the following is a specification, reference being had therein to the accompanying drawings.

This invention relates to carbureters for internal combustion engines, and especially to certain features of construction whereby certainty of initial action, and ease and exactness of control are obtained together with simplicity and readiness of adjustment.

The invention consists in the matters hereinafter set forth, and more particularly pointed out in the appended claims.

Referring to the drawings, Figure 1 is a view in longitudinal section through a carbureter which embodies features of the invention, taken in the axial plane of the engine or outlet port. Fig. 2 is a section on line $x-x$ of Fig. 1. Fig. 3 is a view in vertical section taken on line $y-y$ of Fig. 2. Fig. 4 is a perspective view in detail of the throttle valves. Fig. 5 is a detail of a modified form of float and valve lever connection. Fig. 6 is a detail of a valve stem lock washer. Fig. 7 is a diagram illustrating position of a single valve closure covering two inlet ports, the straight line indicating the closure arm and the arrows the inlets and outlets. Fig. 8 is a similar diagram showing both inlets open. Fig. 9 is a diagram showing the upper inlet open and the lower closed. Fig. 10 is a diagram showing the upper inlet closed and lower inlet open.

In the drawings, the base of the carbureter is a vertically disposed plane metal cylinder, whose bottom 1 is preferably integral with its side wall 2; an axial, hollow conical core 3, likewise preferably integral with the bottom, extends up through the cylinder and the annular space between the core and side wall comprises a float chamber. A pair of radial lugs 4 and 5 are formed on the wall of the cylinder in vertical alinement. The lower lug 4 is hollow, communicating with the interior of the cylinder, and a nipple 6 depending therefrom is exteriorly screw-threaded or otherwise suitably fitted for a fuel pipe connection. The nipple is counterbored and screw-threaded to receive a screw-plug 7, that extends quite through the bottom of the lug. The latter is preferably slightly raised

above the float chamber bottom to prevent sediment from settling thereon. The screw plug is axially apertured and counterbored at its upper end as a valve seat for a conical, 60 needle-valve closure 8, which is secured on a vertical, longitudinally reciprocable stem 9. The latter extends through an aperture in the upper side of the lug 4 and a bushing 10, screw-threaded or otherwise secured in the 65 upper lug 5. The stem is squared where it passes through the bushing, for a square adjusting nut 11 which is held in a corresponding guide aperture 12 in a lock washer 13, that is seated in the upper recessed face of 70 the bushing, a notch 14 in the washer margin engaging a pin or lug in the bushing recess, or other convenient means being used to prevent inter-rotation of the parts. The hollow shield 15 of suitable design is set or screwed 75 on the upper end of the bushing 10, to guard the stem.

The adjacent faces of the lug 4 and bushing 10 are counterbored to hold a gage glass 16, gaskets being interposed between the 80 ends of the glass and the metal to make tight connection, and suitable index marks being placed on the glass, so that it acts as a sight gage for the float chamber, while it houses the needle valve stem and permits view of 85 the latter so that its action can be readily observed.

An annular hollow metal float 17 in the float chamber is operatively connected to the needle-valve stem 9 by a lever 18, turned 90 on a pivot pin 19 in the cylinder wall. The outer end of this lever is bifurcated, and in the preferred form of construction its extremities are vertically slotted for receiving pintles 20 at diametrically opposite points in 95 a gimbal ring 21, which encircles the float, and in turn is pivoted thereto by pins 22 on the float in a diameter at right angles to the pintle diameter, the whole being in effect the usual gimbal connections used for a compass 100 or the like. Or the upright arms of the lever may have slotted engagement with diametrically opposite pins 23 on the float without the intervention of the ring. The other end of the lever 18 is forked to embrace a collar 105 24 which is channeled to receive the lever, the walls of the channel being preferably convex or rounded so as to rock on the lever as it moves up and down. The collar is adjustably screw-threaded on the valve stem 9. 110 An annular dished cover 25 closes the float chamber.

A cylindrical closed casing 26 sets over the upper end of the float chamber, a tight joint being formed by a flange 27 engaging the cover margin and cylinder wall; and an outlet sport 28, preferably circular, through which the contents of the carburetor is drawn by the engine piston, is formed in the casing wall diametrically opposite the sight gage glass of the float chamber, the casing walls being carried out as a hollow nipple fitted for the usual engine connections. Round air inlet ducts 29 and 30 are similarly formed in arms projecting radially from the cylinder casing at diametrically opposite points and 15 at right angles to the axial plane of the outlet. One of these, 30, may be conveniently connected to a pipe which is heated by the engine exhaust or other suitable means, whereby warm air may be drawn into the 20 vaporizing chamber.

A deflector in the chamber consists of a flat plate 31 at the base of the chamber, provided with a central aperture 32 somewhat larger than the top of the float chamber core 25. Outwardly concave wings 33 extend upwardly from the apertured margin of the plate with which they are preferably integral, and are so arranged and disposed as to cover the diametrically opposite air inlets 29 and 30, and to deflect the incoming currents down and around the chamber. A bridge 34 connects the top margins of the wings; the deflector is secured by screws or the like to the casing.

35 An upright stem 36 is supported by a horizontal cross-arm 37 in the core 3, the parts being preferably formed integrally with the core. A horizontal duct 38 extends quite through the lower cross-arm opening at each 40 end into the float chamber, preferably above the chamber bottom, and connects with a vertical central duct 39 in the upright stem 36, the conical wall of the core and the apertured stem forming in effect an atomizing 45 valve which discharges upward through the base of the vaporizer chamber. At the mouth of the duct 39, a conical valve seat is formed on which a vertically reciprocable, conical closure 40 is adapted to set. A vertical stem 41 carries the closure and has screw-threaded engagement with an aperture in the deflector bridge 34, its upper end passing through the casing, being adjusted by a hand wheel 42. In the preferred form 50 of construction, a conical gauze or perforate shield 43 over the vaporizing valve assists in diffusing the spray.

An auxiliary capillary duct 44 is formed in the core stem 36, its upper end opening into 60 a cup-shaped mouth 45 close to the main duct valve seat and at about the upper level to be maintained in the float chamber contents. Its lower end opens horizontally into the float chamber.

65 The outlet port may be closed by a throt-

tle valve which consists of a cylindrical segment 46 concentric with and bearing against the inner face of the upper casing wall, with an inwardly extending radial arm 47 having a boss 48 whose axis coincides with the casing axis. This boss is journaled or rotatable in a central boss 49 in the chamber casing through which it extends. The segment of the valve is of sufficient extent to completely close the outlet.

70 The air inlet ports 29 and 30 are controlled by a single valve, which comprises a cylindrical segment 50 concentric with and bearing against the inner face of the casing wall, which extends around the major portion of the 75 casing wall, so that it may be made to close both the air inlet ports simultaneously. An aperture 51 in the segment, of the same size as one of the air inlet ports 29 is located so that when the opposite inlet 30 is just 80 uncovered by the segment, the other inlet 29 registers with the segment aperture. Thus both ports may be opened and closed independently or simultaneously.

An inwardly extending arm 52 preferably 90 integral with the segment 50, is provided with a boss 53 whose axis is coincident with the casing cylinder, and is journaled in the boss 48 of the outlet valve arm, and in turn, forms a bearing for the upper portion of the 95 rotatable valve stem 41.

The throttle, air inlet and atomizing valve closure are operated by a single throttle lever 54, which is counterbored at its inner 100 end to receive both the inner inlet valve boss 53 and the outer mixture outlet valve boss 48. A set screw 55 adjustably secures the boss 53 to the throttle lever boss, and another set screw 56 sets up the split lever hub so that it grips the other boss 48. A split 105 collar 57 on the stem 41 above the bosses, is clamped in place by a screw 58, and interlocked with the throttle lever by the pin 59. Thus the necessary angular relations and other adjustments in position between the 110 various closures are obtained so that the lever operates them properly. Outer lugs 60 are suitably disposed on the chamber casings for bolting or otherwise securing them together.

115 As a further detail of construction, a drain is provided for the float chamber, which consists of a depending nipple 61 on the chamber bottom interiorly screw-threaded to receive a screw-plug 62 which normally closes an 120 oblique duct 63 in the nipple wall.

The operation of the carburetor is automatic, after the float chamber is once filled. Thereafter, if the engine which it supplies is stopped, for any length of time, or if the 125 level in the float tank falls an appreciable distance below the needle valve seat, the auxiliary duct holds a drop of liquid in its cup close to the nozzle mouth, so as to supply a sufficient amount to insure initial action. 130

By arranging the inlet valves and vaporizing valve to close before the outlet is closed, the carburetor may operate with the limited amount of air through the vaporizer and the fuel coming through the auxiliary duct.

5. The gage glass serves a double purpose as housing for the fuel valve stem and as gage for the float tank, thus enabling the operator to instantly detect any lodgment from impurities in the pipes or failure of fuel supply. The shield perfectly guards the stem, and its ready removal allows quick adjustment of the valve.

10 The distribution of the air inlet ports and deflector prevents any dead spaces in the chamber, so that there is a uniform mixture, and the hot air duct also allows the introduction of a heated mixture to the engine cylinder.

15 20 The one lever control gives simplicity of action and the valves controlled by it are readily adjusted to obtain the proper interaction. The valve bearing surfaces are large and so resist wear, but when loose, may be easily refitted or replaced.

25 The design and construction may be varied without departing from the spirit of the invention and I do not care to limit myself to any particular form and arrangement of 30 parts.

What I claim as my invention is

1. A carburetor comprising a float chamber, a vaporizing chamber over the float chamber, an atomizing valve discharging from the float chamber into the vaporizing chamber, opposite air inlet ports in the vaporizing chamber, a valve closure within the vaporizing chamber, adapted to close said ports either independently or simultaneously, deflecting means opposing the air ports, an outlet port in the vaporizing chamber, a closure for the port within the chamber, and a throttle lever controlling the atomizing valve and inlet and outlet closures.

45 2. A carburetor comprising a float chamber, a cylindrical vaporizing chamber over the float chamber, an atomizing valve discharging from the float chamber into the vaporizing chamber, opposite air inlet ports in the vaporizing chamber, a cylindrical segmental closure within the vaporizing chamber, adapted to close said ports either independently or simultaneously, deflecting means opposing the air ports, an outlet port 50 in the vaporizing chamber, a cylindrical segmental closure for the port within the chamber, and a throttle lever controlling the atomizing valve and inlet and outlet closures.

55 3. A carburetor comprising a float chamber, a vaporizing chamber over the float chamber, an atomizing valve discharging from the float chamber into the vaporizing chamber, opposite air inlet ports in the vaporizing chamber, a valve closure within the 60 vaporizing chamber, adapted to close said

ports either independently or simultaneously, deflecting means consisting of a centrally apertured disk provided with outwardly concave wings opposing the air ports, an outlet port in the vaporizing chamber, a closure for the port within the chamber, and a throttle lever controlling the atomizing valve and inlet and outlet closures.

4. A carburetor comprising a float chamber, a vaporizing chamber over the float chamber, an atomizing valve discharging from the float chamber into the vaporizing chamber, opposite air inlet ports in the vaporizing chamber, a valve closure within the vaporizing chamber, adapted to close said ports either independently or simultaneously, deflecting means consisting of an annular, dished cover over the float chamber and a centrally apertured disk secured over the cover, provided with outwardly concave wings 85 opposing both air inlets, an outlet port in the vaporizing chamber, and a throttle lever controlling the atomizing valve and inlet and outlet closures.

5. A carburetor comprising a float chamber, a vaporizing chamber over the float chamber, an atomizing valve discharging from the float chamber into the vaporizing chamber, opposite air inlet ports in the vaporizing chamber, a valve closure within the vaporizing chamber, adapted to close said ports either independently or simultaneously, deflecting means consisting of an annular, dished cover over the float chamber and a centrally apertured disk secured over 90 the cover, provided with outwardly concave wings opposing both air inlets and a gauze cone hood over the disk aperture, an outlet port in the vaporizing chamber, a closure for the port within the chamber, and a throttle lever controlling the atomizing valve and inlet and outlet closures.

6. A carburetor comprising a float chamber, a cylindrical vaporizing chamber over the float chamber, an outlet port on the 110 wall of the vaporizing chamber, a cylindrical segmental closure for the port bearing against the inner face of the atomizing chamber wall, provided with a radial arm, whose inner end is journaled concentrically 115 in and extends above the top of the chamber casing, a pair of diametrically opposite air inlet ports in the vaporizing chamber, a cylindrical segmental closure bearing against the inner peripheral face of the vaporizing chamber for the major portion of its circumference, adapted to open and close the inlet ports both independently and simultaneously, provide with a radial arm whose inner end is concentrically journaled in and

120 extends through the outlet closure arm, a deflector having wings opposing the inlet ports and a bridge connecting the wings, an atomizing valve, a stem for the atomizing valve 125 closure, having screw-threaded engagement 130

with the deflector bridge, concentrically journaled in and extending beyond the inner end of the air inlet port closure and a throttle lever adjustably secured to bearing ends of 5 the outlet and inlet closure arms, and to the said stem.

7. A carbureter comprising an annular float chamber, a vaporizing chamber above the float chamber in axial alinement there- 10 with, an upright axial stem integrally secured by cross-arms in the aperture of the annular chamber, a horizontal feed duct ex- 15 tending through one of the cross-arms and opening into each side of the float chamber at an interval above the bottom, a vertical feed duct extending from the cross duct to an apertured valve seat at the upper end of the stem, a closure for the seat, an auxiliary duct of small bore from the float chamber 20 opening near the upper end of the stem, a fuel valve for the float chamber, inlet and outlet valves in the vaporizing chamber, and means for operating said inlet and outlet valves and closure.

25 8. A carbureter comprising an annular float chamber, having a central inner wall, a cylindrical vaporizing chamber over the float chamber, an atomizing valve whose casing comprises the conical, inner wall of 30 the float chamber and an apertured stem

secured by an apertured cross-arm axially within said inner wall, and a closure, adapted to be seated on the apertured end of the stem, secured on the upper end of a rod ex- 35 tending upward through the vaporizing chamber, an auxiliary feed duct extending through a cross arm and longitudinally through the stem, provided with a mouth near the upper end of the stem at the normal level of the float chamber contents, and air and fuel supply 40 and throttling means.

9. In a carbureter having a float chamber and a vaporizing chamber, an atomizing valve having an annular inspirating mouth and a fuel feed duct concentric therein, and 45 means adapted to maintain a small quantity of fuel liquid near the inspirating mouth independently of fluctuations in the level in the float chamber contents, consisting of a capillary duct leading from the float chamber 50 provided with a small, liquid retaining outlet at substantially the level of the float chamber contents, within the inspirating mouth near the outlet of the main duct.

In testimony whereof I affix my signature 55 in presence of two witnesses.

ERNEST N. BRODERICK.
